W. F. Moseley,
Design for Collars.

D. No. 2849.

Patented Dec. 17, 1867.

George W. Allen
A. N. Henman

W. F. Moseley by Albany Lewis
D. No. 2849

United States Patent Office.

WILLIAM F. MOSELEY, OF BROOKLYN, NEW YORK.

Design No. 2,849, dated December 17, 1867.

DESIGN FOR A PAPER COLLAR.

The Schedule referred to in these Letters Patent and making part of the same.

TO ALL WHOM IT MAY CONCERN:

Be it known that I, WILLIAM F. MOSELEY, of Brooklyn, in the county of Kings, and State of New York, have invented, originated, and designed a new and useful Design for Paper Collars; and I do declare that the following is a full, clear, and correct description of the same, reference being had to the accompanying drawing, making a part of this specification, in which—

Figure 1 is a view of a paper collar having upon it my design.

Figure 2 is a view of a paper collar folded, having upon it my design.

The nature of my invention consists in placing upon a paper collar, directly below the point of folding the same, an impression representing a continuous stitching, and this is placed upon paper collars made by me to distinguish them from paper collars made and sold by other manufacturers.

The design is clearly shown in the drawing making part of this application.

What is claimed as new, is—

The design for paper collars substantially as shown and described.

WILLIAM F. MOSELEY.
